UNITED STATES PATENT OFFICE.

ALBERT F. MOTSCH, OF ST. LOUIS, MISSOURI.

SUSPENDERS.

No. 911,743.

Specification of Letters Patent.

Patented Feb. 9, 1909.

Application filed October 8, 1907. Serial No. 396,509.

To all whom it may concern:

Be it known that I, ALBERT F. MOTSCH, a citizen of the United States, and resident of St. Louis, Missouri, have invented certain 5 new and useful Improvements in Suspenders, of which the following is a specification containing a full, clear, and exact description, reference being had to the accompanying drawings, forming a part hereof.

10 My invention relates generally to suspenders, and more particularly to the end straps thereof; and the object of my invention is to provide means on the end straps for engaging the waistband of drawers to support the
15 same while the suspenders are in use.

My invention consists in a flexible strap, which is provided with a suitable fastening device, and which strap is fixed to the rear side and lower portion of one of the ends of 20 the end strap of the suspenders.

My invention further consists in certain novel features of construction and arrangement of parts, which will be hereinafter more fully set forth, pointed out in the claim, and illustrated in the accompanying drawings, in

which:—

Figure 1 is a perspective view of one of the end straps of a pair of suspenders with my improved drawer supporting loop thereon;
30 Fig. 2 is a perspective view of a portion of the end strap, with the supporting strap or loop secured thereto, and in an open position; Fig. 3 is a vertical section taken through a portion of the end strap and the supporting strap; Fig. 4 shows a portion of a supporting strap constructed of cloth, and to which my invention is applied.

35

Referring by numerals to the accompanying drawings:—1 designates a waistband of pants, 2 the waistband of the drawers, and 3 the strap which is sewed to the waistband of the drawers.

4 designates the end strap of the suspenders, and secured by stitching, or in any suitable manner, to the rear side and lower portion of one of the ends of said end strap is the upper end of a short strap 5, of leather, or analogous material; and secured to the upper

portion of said strap is the ball portion 6 of an ordinary glove fastener, the socket portion 7 of which is arranged in the lower end of the strap 5. 50

When the lower portions of the end strap are buttoned to the waistband of the trousers, the strap 5 is passed around beneath the strap 3 on the drawers band, and the lower end of said strap 5 is fastened to the upper portion by engaging the socket 7 on the ball 6; and, when so secured, the loop occupies a position immediately to the rear of one of the lower portions of the end strap, and the drawers are supported in a convenient manner and with their weight or pull direct upon the suspenders. 55 60

The supporting straps of my improved device can be readily positioned on end straps of cloth or leather, are entirely hid from view when in use, are very compact, and conveniently hold and support the drawers in a comfortable manner, and without tearing or injuring the fabric of which the drawers are formed. 65 70

I claim:—

The combination with the end strap of suspenders, in which end strap is formed a button hole, of an independent flexible strap the upper end of which is stitched to the rear face of one of the ends of said end strap above the button hole therein, and the free end of which strap extends below the corresponding end of the end strap, a socket fastener secured to the lower free end of the strap, and a fastening stud secured to the upper portion of the strap adjacent the point where the same is stitched to the end strap, thus forming a loop, which occupies a position immediately to the rear of the portion of the end strap provided with the button hole. 75 80 85

In testimony whereof, I have signed my name to this specification, in presence of two 90 subscribing witnesses.

ALBERT F. MOTSCH.

Witnesses:

M. P. SMITH,
E. L. WALLACE.
